CLAIM

The ornamental design of an industrial vehicle armrest as shown and described.

DESCRIPTION

FIG. 1 is a top view of an embodiment of an industrial vehicle armrest illustrating our new design;

FIG. 2 is a bottom view thereof;

FIG. 3 is a front view thereof;

FIG. 4 is a back side view thereof;

FIG. 5 is a right side view thereof;

FIG. 6 is a left side view thereof;

FIG. 7 is a back, bottom, right perspective view thereof;

FIG. 8 is a back, bottom, left perspective view thereof;

FIG. 9 is a front, top, right perspective view thereof; and,

FIG. 10 is a front, top, left perspective view thereof.

The broken lines in the drawings represent portions of the industrial vehicle armrest that form no part of the claimed design and are considered necessary to show the environment in which the design is associated.
